UNITED STATES PATENT OFFICE

146,131

DESIGN FOR A DISPENSING MACHINE FOR BEVERAGES AND ICE CREAM

Joseph A. Chambers, Memphis, Tenn.

Application December 3, 1945, Serial No. 124,268

Term of patent 14 years

(Cl. D52—2)

To all whom it may concern:

Be it known that Joseph A. Chambers, a citizen of the United States, residing at Memphis, in the county of Shelby and State of Tennessee, has invented a new, original, and ornamental Design for a Dispensing Machine for Beverages and Ice Cream, of which the following is a specification, reference being had to the accompanying drawing, forming part thereof, wherein—

Figure 1 is a rear perspective view of a dispensing machine for beverages and ice cream, showing my new design.

Figure 2 is a front perspective view of the same.

I claim:

The ornamental design for a dispensing machine for beverages and ice cream, as shown.

JOSEPH A. CHAMBERS,
